UNITED STATES PATENT OFFICE.

MATTHIAS BROCK, OF BOSTON, MASSACHUSETTS, ASSIGNOR TO MCKAY & COPELAND LASTING MACHINE COMPANY, OF PORTLAND, MAINE.

MACHINE FOR PREPARING VAMPS FOR LASTING.

SPECIFICATION forming part of Letters Patent No. 352,851, dated November 16, 1886.

Application filed June 11, 1886. Serial No. 204,853. (No model.)

To all whom it may concern:

Be it known that I, MATTHIAS BROCK, of Boston, county of Suffolk, and State of Massachusetts, have invented an Improvement in 5 Machine, for Preparing Vamps for Lasting, of which the following description, in connection with the accompanying drawings, is a specification, like letters on the drawings representing like parts.

10 When applying the upper to a last in that step of manufacturing boots and shoes called "lasting," it is necessary, in order to do good work, that the toe of the upper be drawn smoothly about and fitted snugly to the toe of the last, and that the edges of the upper folded about the toe and under the bottom of the last be slitted, so that one part may somewhat overlap the other and avoid plaits in the upper next the bottom of the last.

15 20 I have provided and shall hereinafter describe a machine for clamping the edges of the upper about the toe and outside of but independently of the toe of the last while the latter is being fitted into the upper, the machine also slitting the edges of the upper about its 25 toe part preparatory to turning the said edges over upon the bottom of the last, as will be described.

30 In my improved machine the upper of the boot or shoe to be lasted is clamped at and about its toe part and held while a presser, acting upon the bottom of the last provided with an inner sole, is crowded down into the upper, the latter being thereby stretched, and 35 the stretching having been completed, or substantially so, the edge of the vamp about the toe is slitted, and, if desired, when slitting the edge of the upper, a portion of the material may be cut out, leaving a notch more or 40 less V-shaped.

45 Figure 1, in side elevation, represents a sufficient portion of a machine for preparing vamps for lasting to enable my invention to be understood; Fig. 2, a front end elevation thereof; Fig. 2^a, a perspective view of the jaws; Fig. 2^b, a detail showing the jaw-closing lever; Fig. 3, a top or plan view of Fig. 1; Figs. 4 to 50 7, details showing the jaws for holding the slitting knives or cutters; and Fig. 8 is a partial sectional detail to show an upper being stretched to be fitted to a last.

The frame-work A, of suitable shape to support the working parts, has pivoted upon it by a suitable bolt or pivot, A', an arm, A², which at its forward end has pivoted to it, as 55 at a, the upper ends of two links, B, shown as slotted at their lower ends, (see Fig. 1,) to embrace suitable pins or projections, b, extended from a lever, B', having its fulcrum at B², the said lever being forked at its pivoted end to 60 embrace a hub or bearing-piece, B³, forming a rigid part of the frame-work.

The right-hand end of the lever B' (see Fig. 1) has connected to it a link, B⁴, which in practice will be jointed to a suitable treadle at 65 the floor under the bench or table upon which the base of the frame-work A is mounted, the said treadle being acted upon by a suitable spring or weight, which will normally keep the treadle and the lever B' elevated. 70

Fig. 1 shows the lever B' as fully depressed, the different parts of the machine being in the position that they will occupy when the upper has been stretched and slitted. The movement of the lever B' raises and lowers 75 the arm A². This arm, at its front end, receives the shank D of the presser-foot d, which is to act upon the bottom of the last or inner sole thereon, and press it snugly down into the upper, while the said upper is held by the 80 jaws, to be described, the said shank being surrounded by a spiral spring, d', the upper end of which abuts against a shoulder, d², (see Fig. 2,) at the front end of the arm A², the shank of the said presser being free to slide 85 up through the hole in the said arm whenever, in the descent of the arm A², the foot d meets the inner sole on the last, it then acting to press the last into the upper of the boot or shoe. 90

The upper of the boot or shoe is opened out, and has its toe portion with the inner side of the upper uppermost placed between the jaws h h'. The outer face of the upper is laid upon the rest d⁴, which is preferably a 95 piece or strip of rawhide laid upon and forming the surface of the bed-plate d⁵.

The arm A² has pivoted to it by the pivot-screw e (see dotted lines, Fig. 1) the holders e' e², which at their outer ends are capable of 100 being adjusted about their common pivot e, by screws e³ and e⁴, in slots made in the said

arm A^2 , as shown in Fig. 3. These holders, provided with segmental grooves, receive in them the blade or knife carrying blocks $e^5 e^6$, the said blocks being secured in place by 5 screws 22. The blades or knives c (see Figs. 1 and 2, full lines, and in Fig. 5 by dotted lines) are secured in radial slots of the said blocks by screws c^2 , passed into diagonal holes, (see Fig. 6,) the said screws impinging against the shanks of the blades or knives after they have been placed in the said slots, the slots preferably occupying, as shown, radial positions with relation to the center of the curve represented by the curve of the last. These blades cut through the vamps and upon the rawhide d^4 , referred to, when slitting or cutting the vamps. The extra movement of the arm A^2 , after the foot d has been arrested, as described, enables the upper 5 to be held firmly, while the arm A^2 continues its descent to place the blades or cutters in contact with and to cut through the upper while held by the jaws $h h'$. The under jaw, h' , has a number of toothed or scored projections, which, when the jaws are fully forward, enter slots in the bed-plate, so that the said 5 projections extend toward the foot d , between the blades or knives c . The upper jaw, h , provided with a series of toothed or scored projections to co-operate with the toothed projections of the jaw h' to form a clamp, is pivoted at h^3 upon an ear or lug arising from the lower jaw, h' . The upper jaw, h , is surmounted by a metal plate, h^4 , attached to the said upper jaw 5 at the front end by a bolt, h^5 , the bolts $h^5 h^6$, which are inserted through the rear end of the said plate, being also extended through the said upper jaw, and also through a spring, h^7 , preferably a block of india-rubber, after which which are inserted through the rear end of the said plate, being also extended through the said upper jaw, and also through a spring, h^7 , preferably a block of india-rubber, after which 5 the said bolts are passed through a cap, h^8 , and have applied to them suitable nuts, h^9 . The lower jaw, back of the pivot h^3 , has suitable ears, 3, to receive a pin, 4, which serves as a fulcrum for the jaw-closing lever m , having a curved or cam-shaped end, as m' , to act upon a roller, m^2 , mounted upon a pin, m^3 , inserted through two ears, $m^4 m^5$, forming part of or connected to the plate h^4 , the said surface, by its contact with the said roll, causing the jaw h to grasp the upper between it and the lower jaw; but in case of variations in the thickness of the upper, which would do injury, the spring h^7 permits the plate h^4 to yield to a limited extent.

When the arm A^2 is fully lifted, and while the parts are in position for the edge of the upper about its toe to be placed between the jaws of the clamp, the jaw-closing lever is so turned upon its fulcrum 4 as to bring the notch m^5 below the roller m^2 , and in such condition the jaws $h h'$ are free to open, the rear end of the upper jaw, h , being the heavier. The lever m is operated by a link, n , jointed to it, the said link being jointed to the lever B' at n^2 . The lower jaw, h' , is acted upon by a spring-arm, n^3 , (shown chiefly by dotted lines, Fig. 1,) which at its lower

end is bolted to the frame-work by the bolt n^4 , the said spring normally acting to move the jaws backward, or to the right in Fig. 1. 70 The effective pressure of this spring may be augmented, when desired, by an auxiliary spring, o , (shown by dotted lines, Fig. 1, as a spiral spring,) one end of which bears against the said spring n^3 , while the opposite end of the spring o is acted upon by a shoulder of a screw, o' , screwed into an ear, o^2 , secured to or forming part of the frame-work A . The slits 8 are made entirely through the blocks $e^5 e^6$ from their convexed to their concaved walls 80 or faces, thus permitting the blades or knives c to be adjusted in the direction of their width, to thus enable the inner corners of the blades to occupy a position more or less from the curved end of the last. 85

In Figs. 4 and 5 the positions of the blocks $e^5 e^6$ have been reversed, as may be the case, if desired, to vary the introduction of the slit in the toe of the upper.

When the machine is ready to be started, 90 the jaws $h h'$ are pushed back toward the right in Fig. 1 by a spring, n^3 , ready to be moved forward, if need be, by strains exerted upon the upper. The operator places the last, with the inner sole laid thereon or attached thereto 95 in usual manner, within the upper, and the toe of the upper is then placed between the jaws $h h'$, the operator holding the upper with the last therein in his hand. In this position the operator depresses the lever B' , and by the link n turns the jaw, causing the lever m to close the jaws $h h'$ firmly upon and so as to clamp the edges of the upper. This done, the lever B' , in its further descent through the links B , effects the depression of the arm A^2 , bringing the foot d against the inner sole, S , lying upon the bottom of the last, forcing the last into and stretching the upper, and, finally, in the descent of the arm A^2 , the knives or blades c meet the upper, as described, between the 100 points where it is grasped by the toothed projections of the jaws $h h'$, cutting or slitting the said edges. 105

During the operation of crowding the last L into the upper, both held by the operator, 110 should the upper held by the jaws $h h'$ be too short to stretch properly, then the upper would be torn, were it not for the spring n^3 , which, under strain sufficient to draw the upper from the jaws, will permit the jaws $h h'$ to move forward against the strain of the said spring n^3 ; but, finally, the ends of the jaws will meet shoulders cut into or forming part of the body d^5 , and thereafter undue or excessive strain will be compensated for or counteracted by the 115 further yielding or compression of the spring d' , surrounding the shank D .

The blocks $e^5 e^6$ are slotted through from their concaved to their convexed edges to receive the blades or knives c , the said blades 120 or knives being thus free to be adjusted in the direction of their width, in order to adapt the inner edges or corners of the said bolts or knives to the shape of the toe of the last being

used, such provision for adjustment being a matter of great convenience, as the toes of lasts vary very considerably in contour, such adjustment being frequently needed even in 5 different sizes of lasts of the same shape.

I claim—

1. In a machine for preparing vamps for lasting, a pair of jaws to grasp the edge of the upper about the toe of the last, combined with 10 a yielding presser-foot, d , to act upon the bottom of the last or the inner sole thereon to crowd the last into the upper, and with means, substantially as described, to actuate the said presser-foot.
- 15 2. In a machine for preparing vamps for lasting, a pair of jaws to grasp the edge of the upper about the toe of the last, and slitting mechanism to cut or slit the edge of the upper while held by the said jaws, combined with a 20 yielding presser-foot, d , to act upon the bottom of the last or on the inner sole thereon to crowd the last into the upper, and with means, substantially as described, to actuate the said presser-foot.
- 25 3. The combination, with the jaws h h' , and the plate h^4 , and a spring, as a^1 , of a jaw-operating lever to close the said jaws, substantially as described.
- 30 4. In a machine for preparing vamps for lasting, a yielding presser-foot to act upon the

bottom of the last or inner sole thereon to force the last into the upper, and the pair of jaws to grasp the edges of the upper about the toe of the last and hold it while the last is being forced into the upper, combined with a spring 35 to permit the jaws to move longitudinally under excessive strain applied to the upper, substantially as described.

5. The lever A^2 and its attached yielding presser or foot d and holders $e' e^2$, with the 40 segmental blocks $e^5 e^6$, adjustable in the said holders and slotted for the reception of the knives or blades to slit or cut the upper, substantially as described.

6. The lever A^2 and the holders $e' e^2$, pivoted 45 thereon, as described, combined with the blocks $e^5 e^6$, slotted as described, and with the blades or knives therein made adjustable in the direction of their width or longitudinally in the said slots or toward and from the toe of the 50 last, to adapt the blades to lasts of different size or curvature, substantially as described.

In testimony whereof I have signed my name to this specification in the presence of two subscribing witnesses.

MATTHIAS BROCK.
